UNITED STATES PATENT OFFICE.

WILLIAM E. VAN DORN, OF CHICAGO, ILLINOIS.

CORRUGATED-METAL CAR END.

Application filed November 19, 1920. Serial No. 425,040.

To all whom it may concern:

Be it known that I, WILLIAM E. VAN DORN, a citizen of the United States, residing at Chicago, county of Cook, State of Illinois, have invented a certain new and useful Improvement in Corrugated-Metal Car Ends, and declare the following to be a full, clear, and exact description of the same, such as will enable others skilled in the art to which it pertains to make and use the same, reference being had to the accompanying drawings, which form a part of this specification.

My invention has for its object to produce a sheet metal panel which will possess a much greater strength to resist forces acting transversely to the plane thereof than do any sheets or panels of which I am aware.

It is known that the corrugating of a metal sheet greatly stiffens it. When subjecting a corrugated sheet to pressure at right angles to its plane, the initial resistance is not nearly as great as it is after a considerable distortion or bowing of the corrugations has taken place. In accordance with my invention, I so construct the corrugations that they are normally bowed lengthwise in planes at right angles to the plane of the sheet, thus securing the advantage of the greater strength of such corrugations at the very instant of the application of a load.

My invention is particularly applicable to railway car construction, especially in the manufacture of metal ends and therefore, viewed in one of its aspects, my invention may be said to have for its object to produce a simple, strong sheet metal panel adapted for use in the construction of walls, particularly ends, of railway cars.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is an elevation of a box car end embodying my invention;

Fig. 2 is a vertical transverse section through the metal end detached from the car;

Fig. 3 is a section taken approximately on line 3—3 of Fig. 1;

Fig. 4 is a view of a modification similar

to Fig. 3, on an enlarged scale, showing only one corner of the car;

Fig. 5 is an elevation of a box car end embodying my invention in a different form from that illustrated in Fig. 1;

Fig. 6 is a section taken approximately on line 6—6 of Fig. 5;

Fig. 7 is a view of a modification similar to Fig. 6, illustrating a means of connecting the metal end to the sides of a car having no corner posts, only one corner being shown;

Fig. 8 is an elevation of an end of a gondola car embodying my invention;

Fig. 9 is a section taken approximately on line 9—9 of Fig. 8;

Fig. 10 is a transverse section on line 10—10 of Fig. 8;

Fig. 11 is an elevation of the end of a box car embodying my invention in a still different form, one side of the car end being broken away;

Fig. 12 is a side elevation of the car body shown in Fig. 11 at the end shown in Fig. 11; and

Fig. 13 is a section taken approximately on line 13—13 of Fig. 11.

In Figures 1 to 3 of the drawings I have illustrated my invention in the form of an end for a box car, the end being made in two panels one arranged above the other. Referring to these figures, 1 and 2 represent respectively the lower and the upper panels, these being conveniently secured together by a riveted lap joint 3. Each of the panels is in the form of a flat sheet having a plurality of parallel corrugations extending from the vicinity of one side edge to the vicinity of the other side edge. In the particular arrangement shown, each entire panel, with the exception of a flat marginal rim-like portion is filled with corrugations, the latter being of approximately uniform depth throughout their length.

In accordance with my invention I bend the corrugations lengthwise transversely of the plane of the sheet without bodily bending the sheet so as to give them an arched or bow-shaped formation. This can be accomplished, without unduly deepening the corrugations, by pressing a portion of each corrugation in one direction from the plane of the sheet and the remainder of the corrugation in the opposite direction from said plane, so that each corrugation lies partly on one side of the sheet and partly on the

90

95

100

105

110

other. Furthermore, by this construction undue stretching of the metal in making the corrugations is avoided. In the arrangement shown, the central section, 4, of each 5 corrugation is pressed outwardly from the plane of the sheet while the two end sections, 5 and 6, are pressed inwardly, all three of the sections being preferably straight. The extreme ends of the corrugations 10 are preferably flattened as indicated at 7, so as to lie in planes which make an obtuse angle with the plane of the sheet. The metal end is fastened to the sides, 8, of the car in any suitable way. The ends are 15 illustrated as terminating in corner posts, 9. The flat marginal portions at the sides of the end extend across the posts and are flanged around the same as indicated at 10. Secured to the inner faces of the posts are 20 vertical reinforcing bars, 11, L-shaped in cross section, one flange of each of these bars being conveniently tied to the post and to the flange, 10, by means of bolts, 12, and the other flange being fastened to the end sections, 5 of the corrugations by suitable rivets, 13. Further stiffness may be given to each corner by means of an angle iron, 14, one flange of which is riveted to the member 11 as indicated at 15, and the other of which 25 is bolted through the corresponding side of the car and through the corresponding flange, 10, by means of bolts, 16.

In Fig. 4 the corrugations are shown as being somewhat longer than in Figs. 1 to 35 3, the flattened ends of the end sections resting against a correspondingly-shaped surface, 17, on the post 18. In addition to the bolts, 19, passing through the post and the flange 10, there are other bolts, 20, extending through the post and the flat marginal portion of the sheet parallel with the longitudinal axis of the car. A reinforcing bar, 21, L-shaped in cross section, is secured by one flange to the post by means of 40 the bolts, 19, and has its other flange riveted to the corrugations as indicated at 22.

In Figs. 5 and 6 there is shown a box car in which the end is made up of three panels, 23, 24 and 25, similar to those heretofore described except that the central sections, 26, of the corrugations are pressed inwardly from the plane of the sheet while the end sections, 27, are pressed outwardly. The entire end is stiffened and reinforced by means 55 of vertical posts or bars, 28, which may conveniently be Z-bars, extending vertically across the end and at the angles between the central sections of the corrugations and the end sections. The side marginal portions 60 are flanged around the posts 9 as in the construction shown in Fig. 3. Further security of attachment to the sides of the car is secured by means of straps, 29, extending along the inner walls of the car sides and 65 having their ends secured by means of riv-

ets, 30, to the inner faces of the flattened ends, 7, of the corrugations. The bolts 12 which pass through the post and the flange 10 also pass through the straps so as to tie the three together.

In Fig. 7 there is illustrated an end similar to that shown in Figs. 5 and 6, applied to a car having thin sides that do not terminate in corner posts. The flat marginal portions at the sides of the end are bent inwardly, as indicated at 31, across the inner walls of the sides, 32, of the car. At each corner is a vertical reinforcing bar having one section or flange, 33, secured to the flattened ends, 7, of the corrugations by rivets, 34; a web, 35, engaging with the extreme end of the car side, and a second flange, 36, overlying the outer face or surface of the car side. Bolts, 37, pass through the flanges 36 and 31 and through the car side so as to tie these three elements together. Further reinforcement of the corner may be secured by means of straps, 38, extending from the corner inwardly or rearwardly to one of the vertical stanchions or posts, 39, that are usually placed along the outside of thin side walls of the kind illustrated; one end of each of the straps being secured in place by the bolts 37 and the other end being riveted or otherwise secured to the member 39.

In Figs. 8, 9 and 10 there is shown an end for a gondola car similar to the construction illustrated in Figs. 1, 2 and 3, the end in this instance, however, being made of a single panel and it being shown applied to thin side walls, 40, with which no corner posts are associated. The side marginal portions of the panel are flanged around the sides, as indicated at 10, in the same manner as heretofore explained, and the corners are reinforced by means of the L-shaped bars, 11, and the angle irons, 14, corresponding to the parts similarly numbered in Fig. 3. Around the top of the car is a bulb angle, 41, one flange of which is horizontal and one flange of which is vertical and arranged behind the upper flat marginal portion of the panel, the panel and this vertical flange being fastened together by rivets, 42. The panel is flanged outwardly at its lower end as indicated at 43 and is riveted to the upper flange of the end sill, 44, or other suitable floor structure.

In Figs. 11 to 13 I have illustrated panels having additional reinforcing means, the panels being shown as applied side by side to form the end of a box car, and the corrugations in the panels extending vertically. Referring to these Figures, 51, 50 and 52 represent respectively a central and two side panels which, together, form a complete end. The panels are fastened together in any suitable way as, for example, by means of riveted lap joints, 53. The corrugations in this form of my invention are vertical, each

corrugation comprising a central section, 54, pressed inwardly from the plane of the sheet and upper and lower sections, 55 and 56, pressed outwardly. The extreme upper and lower ends of the corrugations are flattened, as indicated at 7, in the same way as in the other forms of the invention illustrated. The marginal side portions of the end are flanged, as indicated at 57, so as to overlie 10 the outer faces of the sides, 58, of the car body. If desired, reinforcing bars, 59, and 60, may extend transversely across the end at the angles between the central and end sections of the corrugations. The stresses 15 from these reinforcing bars may be in part transferred to the sides of the car body by means of suitable straps, 61, extending along the sides of the car on the exterior thereof and bent laterally at their outer ends, as 20 indicated at 62, so as to overlie portions of the reinforcing bars 59 and 60; the part 62 being riveted or otherwise secured to these bars, conveniently by means of rivets, 63, passing through the same, through the bars, 25 and through the metal ends and, if desired, by means of additional bolts, 64, passing only through the member 62 and the reinforcing bars.

Across the flattened upper ends of the corrugations, and secured to such flattened ends by rivets or other suitable means, is a plate, 30 65. A similar plate, 66, extends across and is secured to the flattened portions at the extreme lower ends of the corrugations. Between the plates 65 and 66 extend one or 35 more ties or tension members; there being shown three such members, 67, 68 and 69, the member 67 extending across the longitudinal center-line of the central panel and the other 40 two members being located at the middle of the other two panels. These ties or tension members constitute the strings to the bows formed by the bent corrugations and, when pressure on the inner side of the metal end 45 tends to straighten the corrugations, this action will be resisted by the tension members.

The lower ends of the intermediate reinforcing bars, where vertical reinforcing bars 50 are employed as illustrated at 28 in Fig. 5, may be secured to the end sill, 70, or other part of the car floor frame by suitable fastening means 71.

While I have illustrated and described 55 with particularity only a few preferred forms of my invention, I do not desire to be limited to the particular details thus illustrated and described; but intend to cover all forms and arrangements coming within the 60 definitions of my invention constituting the appended claims. Furthermore, I desire to have it understood that the word "bent" is used in the claims more in the sense of shape or contour rather than in the sense of a particular process employed in producing such 65

shape. In other words, by "bent" I mean something that is not straight.

I claim:

1. A flat metal sheet having therein elongated stiffening corrugations so shaped that the tops of the ridges and the bottoms of the valleys are bent lengthwise in a plane at right angles to the plane of the sheet. 70

2. A metal sheet having therein stiffening corrugations bent lengthwise in planes at 75 right angles to the plane of the sheet so as to bring portions thereof on one side of the latter plane and other portions on the opposite side of the latter plane.

3. A flat metal sheet having therein elongated stiffening corrugations bent lengthwise in a plane at right angles to the plane of the sheet and each being of approximately uniform depth throughout its length. 80

4. A flat metal sheet having therein stiffening corrugations all of whose longitudinal elements lie in planes at right angles to the sheet and are bent on long sweeping lines in said plane. 85

5. A flat metal sheet having therein stiffening corrugations whose longitudinal elements lie in planes at right angles to the sheet and are bent on long sweeping lines in said plane, each corrugation being of approximately uniform depth throughout its 90 length. 95

6. A metal sheet having therein corrugations bent lengthwise so as to bring the middle portions on one side of the plane of the sheet and the ends on the other side of said plane. 100

7. A metal sheet having therein corrugations each of approximately uniform depth throughout its length bent lengthwise so as to bring the middle portions on one side of the plane of the sheet and the ends on the other side of said plane. 105

8. A metal sheet having therein corrugations bent lengthwise to make them bow-shaped in planes at right angles to the plane of the sheet, and a tie member extending across the concave side of the bent corrugations and secured at its ends to the corresponding ends of the corrugations. 110

9. A metal sheet having therein corrugations bent lengthwise to make them bow-shaped in planes at right angles to the plane of the sheet, the ends of the corrugations being flattened so as to make obtuse angles with the plane of the sheet, and a tie member extending lengthwise of the corrugations across the concave side of the bends and riveted at its ends to said flattened ends of the corrugations. 115

10. A metal sheet having therein corrugations the middle portions of which project on one side of the plane of the sheet and have their longitudinal elements in the form of lines parallel with said plane and the end portions of which are bent so as to pro- 120

- ject to the opposite side of the plane of the sheet and have their longitudinal elements in the form of lines making a slight angle to said plane.
- 5 11. A metal sheet having therein corrugations the middle portions of which project on one side of the plane of the sheet and have their longitudinal elements in the form of straight lines parallel with said plane and 10 the end portions of which are bent so as to project to the opposite side of the plane of the sheet and have their longitudinal elements in the form of straight lines making a slight angle to said plane.
- 15 12. A metal sheet having therein parallel corrugations extending from the vicinity of one edge to the vicinity of the opposite edge and bent lengthwise in planes at right angles to the sheet so as to bring the middle portions 20 on one side of the sheet and the end portions on the opposite side of the sheet.
- 25 13. A metal sheet having flat marginal portions and parallel corrugations extending from one of said marginal portions to the opposite one, said corrugations being bent lengthwise to give them a bow-shape, and the ends of the corrugations being flattened so as to lie in planes making obtuse angles 30 with said flat marginal portions.
- 35 14. A sheet metal car end having elongated corrugations therein, certain of the corrugations being bent in planes at right angles to the plane of the sheet so as to bring portions thereof on one side of the normal plane of the sheet and other portions thereof on the other side of the latter plane.
- 40 15. A flat sheet metal car end having parallel corrugations forming ridges and valleys extending substantially across the same parallel with one of its principal axes, the corrugations being bent so that the ridges and valleys are bow-shaped in planes parallel with said axis.
- 45 16. A sheet metal car end having parallel corrugations extending substantially across the same parallel with one of its principal axes, the corrugations being bent into a bow shape in planes parallel with said axes, and a tie member extending across the bow and secured at its ends to the ends of the corrugations.
- 50 17. The combination with the sides of a car body, of a sheet metal end having horizontal corrugations extending from the vicinity of one of said sides to the vicinity of the other of said sides, said corrugations being bent so that the middle portions lie on one side of the plane of the sheet and the end portions lie on the other side of the plane of the sheet, and means 55 for securing said metal end to said sides.
- 55 18. A metal sheet having therein corrugations bent lengthwise so as to bring the middle portions on one side of the plane of the sheet and the ends on the other side of said plane, and reinforcing bars extending across the sheet transverse to the corrugations and in the vicinity of the juncture of the said middle portions with the side portions.
- 60 19. A sheet metal car end having flat marginal portions and parallel corrugations extending from one of said marginal portions to the opposite marginal portion, said corrugations being bent lengthwise to give them a bow-shape, the ends of the corrugations being flattened so as to lie in planes making obtuse angles with said flat marginal portions, and reinforcing elements attached to 65 said flattened ends of the corrugations.
- 70 In testimony whereof, I sign this specification.

WILLIAM E. VAN DORN.
